UNITED STATES PATENT OFFICE.

CHARLES M. EARL AND BENJAMIN F. WHEELER, OF DETROIT, MICHIGAN.

BEVERAGE-DISPENSING DEVICE.

Application filed May 8, 1922. Serial No. 559,203.

To all whom it may concern:

Be it known that we, CHARLES M. EARL and BENJAMIN F. WHEELER, citizens of the United States, residing at Detroit, in the 5 county of Wayne and State of Michigan, have invented a new and useful Beverage-Dispensing Device, of which the following is a specification.

This invention relates to beverage dispensers and particularly to devices for drawing carbonated beverage from storage tanks charged under comparatively high pressure.

The invention has for its principal objects 10 to provide simple and reliable means for properly drawing and suitably serving carbonated beverage from storage tanks under pressure, in which relief of the high tank pressure is effected to reduce the force of 15 discharge and lessen the resultant effervescent or bead effect upon the beverage when drawn from the tank; to provide for relief of the high gas pressure automatically in 20 the operation of drawing the beverage into the dispenser, and in such manner as to effect an attractive display of the beverage while undergoing relief from such pressure; to provide for confining and utilizing the 25 reduced pressure so as to always maintain 30 the beverage drawn into the dispenser charged with sufficient gas to retain the desired pungency and prevent its becoming flat or stale, as well as to set up the required pressure to facilitate drawing the beverage 35 rapidly into the serving glass without excessive bead; to provide for automatic regulation and control to uniformly maintain the reduced pressure and to safeguard the dispenser against danger from excess pressure; to provide adequate cooling means to meet 40 the requirement of proper low temperature essential to the satisfactory serving of soft drinks, and finally to so embody these features in a device of this character as to secure 45 ornamental attractiveness in design with convenience and facility of operation in which delivery of the beverage in the most uniform and favorable condition is assured.

50 In attaining these objects the invention contemplates briefly the employment of a cooling tank containing a beverage receiving and discharging chamber, a two-way valve controlling delivery to and from said chamber, a rotor in the chamber driven by

the force of the inflowing beverage to distribute the same upon the walls of the chamber and liberate the gas therefrom, a vent port in the top of said chamber for the escape of gas, and a flexible inflatable bag or balloon carrying an open ported valve controlling said vent port and likewise controlling the inflation of said balloon, which in turn sets up and maintains a reduced pressure in said chamber regulated automatically by expansion and contraction of the balloon with movement of the valve controlling delivery to and from said chamber.

A preferred embodiment of the essential features of the invention is illustrated in 70 the accompanying drawings, in which,

Fig. 1 is a view in side elevation of the device as shown in Fig. 1, indicating 75 by dotted lines actuated positions of the normally contracted.

Fig. 2 is a central vertical sectional view of the device as shown in Fig. 1, indicating by dotted lines actuated positions of the two-way valve.

Fig. 3 is a sectional elevation of a group 80 of detached parts comprising the relief valve cup and upper portions of the beverage chamber.

Fig. 4 is a side elevation of the relief valve and indicating by dotted lines the balloon engaged therewith.

Referring to the parts illustrated in the drawings, 1 indicates a cylindrical sheet metal cooling tank adapted to be packed with ice, and provided with a supporting base 2 and a removable top or cover 3. The tank, which is preferably of hollow wall construction, and which may be insulated to prevent sweating exteriorly, is provided with a coil 4 of block-tin pipe connected through the bottom of the tank by a nipple 5 with a feed pipe 6 leading from a storage tank (not shown) containing the beverage under pressure. The coil 4 is distributed upon the bottom of the tank being reduced and extended vertically centrally thereof, and rising within the coil and extending through an opening 3' in the cover 3 is a beverage receiving chamber 7 which comprises a sheet metal cylinder 8 having at its upper end a shouldered flange 8' for supporting the edge of the aperture 3' of the cover, and for the reception of a packing gasket 9 upon which is mounted a glass cyl- 100 105 110

inder 10 extending above said cover. The lower end of the cylinder 8 is closed by fixed engagement with a flanged head 11 having integral supporting legs 12 and provided with a radial inlet passage 13 which receives a threaded exterior nipple 14 and communicates interiorly with a stand pipe 15 seated in a hollow boss 16 formed centrally of said head, and an outlet passage 17 is formed through a nipple 18 threaded into the flanged wall of said head. The upper end of said chamber is closed by a dome cap 19 peripherally flanged to receive a gasket 20 in engagement with the upper end of the cylinder 10, and said cap is apertured as at 21 to receive the body of a tubular valve casing 22. Said casing extends through said aperture and has a collar 23 seating a packing washer 24 upon said dome cap and carries at its inner end a reduced plug extension 25 internally screw-threaded as at 26 for engagement with the screw-threaded upper end of a tubular tie rod 27 which is spaced within the stand pipe 15 and secured at its lower end through the boss 16 of the head 11 by a nut 27', said valve case and tubular tie rod thus serving to confine the several parts of the chamber together, and said rod also functioning in connection with a passage 28 through said plug to form a drain for drippage from the valve case.

At the upper end, said stand pipe is contracted to snugly embrace the tie rod as at 29 and is formed with a plurality of jet apertures 30 for the discharge of beverage in an upward radially diverging direction therefrom, and rotatably embracing the tie rod between said stand pipe and the plug 25 of the valve case is a disk rotor 31 mounted on a sleeve 32 and having a plurality of curved radially and circumferentially extending propelling blades 33 adapted to be engaged and driven by the liquid beverage issuing from the jets 30 of the stand pipe and to deflect and distribute the beverage upon the wall of the glass cylinder 10 allowing the liquid to settle and the liberated gas to rise to the top of the beverage chamber.

To provide relief for the higher gas pressure and to insure the retention of a lower pressure in the beverage chamber, an outlet passage 34 is formed in the plug 25 of the valve case 22 in communication with a valve port 35 formed in a raised seat on said plug axially within said valve case, and normally seated in said port to move vertically in said case is a valve stem 36 having a passage 37 axially therethrough. Said stem is formed with an enlarged cupped head 38 and a spaced collar 39 having peripheral projections 39' for sliding engagement with the wall of the valve case and to provide clearance for the by-passage of gas when said stem is raised from its seat. At its upper end said stem is slightly flared and formed

with serrations 40 for insertion within and engagement under contraction of the elastic neck of an expansible bag or balloon 41, the body of which when inflated is adapted to engage with the outwardly flared upper end 42 of the valve case and effect the raising of the valve and the relief of the pressure which may escape from the valve case through exhaust ports 43 therein. (See Figs. 3 and 4.)

Delivery of the beverage to and from the chamber 7 is controlled by a two-way valve mounted exteriorly of the tank (see Fig. 2), said valve comprising a casing 44 having a return branched inlet passage 45 intersecting an outlet passage 46 opening through a discharge spout 47. Said passages are controlled in common by a rotative valve plug 48 having a diametric passage 49 and provided with a handle 50 by which it may be oscillated to alternatively register the valve passage 49 with the inlet and outlet passages 45 and 46 respectively. One branch of the inlet passage 45 is connected with the inner terminal of the coil 4 by a pipe coupling nipple 51 extending through the wall of the tank and having screw-threaded engagement with the valve case 44, and the other branch of said passage is similarly connected by a pipe coupling nipple 52 with one end of a pipe section 53 which extends partly around the head 11 and is connected at its opposite end with the nipple 14 of the inlet passage 13 of said head, thus establishing connection between the coil and stand pipe through the inlet passage controlled by the valve, the outlet passage 46 controlled by said valve being connected through a nipple 54 with a pipe 55 secured at one end in the nipple 18 of the outlet passage 17 of the chamber 7.

The valve plug passage 49 is normally retained closed in a neutral position intermediate the inlet and outlet passages of the valve case by a spring pressed detent 56 carried in the handle 50 and yieldably engaging a depression 57 in said valve case.

In the operation of the device, movement of the valve handle to the vertical dotted position shown in Fig. 2 will register the passage 49 of the valve plug with both branches of the inlet passage 45, through which and the pipe 53 beverage under pressure in the coil 4 from the supply pipe 6 will be admitted to the stand-pipe 15, from whence it will discharge through the ports 30, engaging and revolving the blades 33 of the rotor, by action of which the beverage will be deflected and spread upon the wall of the cylinder 10, flowing thereon and settling to the bottom of the chamber 7. The gas accumulating in the chamber 7 when released from the inflowing beverage will escape through the passage 34 of the valve case 22 and through the passage 37 of the valve stem 36 into the balloon 41, and as said balloon becomes inflated sufficiently to en-

gage the body thereof, which is normally free from the valve case, with the flared end 42 of said valve case a lifting pressure will then be exerted upon the valve stem 39 increasing with the further expansion of said balloon to the point of overcoming the weight of said stem when the latter will be raised from the seat in the passage 34 allowing the gas to escape through said passage 10 from the chamber 7, as well as through the passage 37 from the balloon into the valve case and through the exhaust ports 43 therein to the atmosphere.

Upon returning the valve handle to its 15 neutral position, the valve stem 39 will automatically seat by gravity immediately the escaping pressure allows the balloon to contract sufficiently to clear the top of the valve case, thus cutting off further escape of pressure through the ports 43 and reestablishing communication between the passage 34 and 20 37 through which the pressure retained by the balloon will be exerted upon the beverage accommodated in the chamber 7. When 25 the valve handle is shifted to the horizontal dotted position indicated in Fig. 2, the passage 49 of the valve plug will be caused to register through the pipe connection 55 with the outlet passage 17 of the chamber 30 7 and with the outlet passage 46 of the valve * spout from which the beverage in said chamber will be discharged under the gas pressure stored in the balloon. The capacity of the balloon is sufficient to retain and set up the 35 required gas pressure to discharge a chamber full of beverage so that when the discharge is cut off by returning the valve handle to neutral any beverage remaining in the chamber will be charged with sufficient gas to prevent "flattening" and will also be retained under the low temperature within the cooler always in suitable condition to serve.

It will be noted that in addition to the 45 lifting leverage exerted upon the relief valve stem by pressure of the wall of the balloon upon the valve case, said stem is also subject to the buoyant lifting tendency of the gas in the balloon and is therefore rendered sensitive and positive in responsive action to variations in pressure, so that liability of injury to the container or balloon resulting from the development of excessive pressure through failure of the valve to lift is entirely 50 eliminated. If, however, the balloon should from any cause become damaged and unfit for use, it may be quickly replaced by a new one upon removal of the valve stem through the open end of the valve case in which it is 55 readily accessible.

A desirable feature in the commercial use of the dispenser is the visual effect produced by the expanding and contracting of the balloon which tends to attract attention to the 60 beverage displayed in the container, while

the surface of the balloon affords prominent space for effectively displaying appropriate matter advertising the goods.

What we claim is:

1. In a beverage dispensing device, a 70 chamber having an inlet for beverage under gas pressure and having an outlet for gas, and a receptacle for gas enclosing said outlet and adapted under predetermined pressure of gas to open said outlet and vent 75 said chamber.

2. In a beverage dispensing device, a chamber having an inlet for beverage under gas pressure and having an outlet for gas, and a buoyant receptacle communicating with and normally closing said outlet and operable under predetermined pressure of gas to open said outlet to vent said chamber. 80

3. In a beverage dispensing device, a chamber having an inlet for beverage under gas pressure and having an outlet for gas, and an inflatable receptacle in communication with said chamber and normally closing said outlet and operable under inflation by pressure of gas to open said outlet and 90 vent said chamber. 85

4. In a beverage dispensing device, a chamber having an inlet for beverage under gas pressure and having an outlet for gas, a valve normally closing said outlet, and a 95 buoyant container for gas communicating with said chamber and operably associated with said valve to effect opening of the latter under predetermined pressure of gas in said container. 100

5. In a beverage dispensing device, a chamber having an inlet for beverage under gas pressure and having an outlet for gas, a valve controlling said outlet, and a yieldable receptacle for gas communicating with said chamber and operatively associated with said valve to effect actuation of the latter under variations of pressure of gas in said chamber. 105

6. In a beverage dispensing device, a chamber having an inlet for beverage under gas pressure and having an outlet for gas, a valve normally closing said outlet and having a passage for gas therethrough, and a buoyant receptacle for gas engaging said valve and operable under pressure of gas admitted through said passage for raising said valve to vent said chamber. 110 115

7. In a beverage dispensing device, a chamber having an inlet for beverage under gas pressure and having an outlet for gas, a valve normally closing said outlet and having a passage for gas therethrough, and an inflatable receptacle engaging said valve and operable under expansion by pressure of gas admitted through said passage for opening said valve to vent said container. 120 125

8. In a beverage dispensing device, a chamber having an inlet for beverage under 130

gas pressure and having an outlet for gas, a valve case communicating with said chamber and having an outlet for gas, a valve normally closing said outlet and having a passage for gas therethrough, and an elastic receptacle embracing said valve and engageable with said valve case upon inflation by pressure of gas admitted through said passage for raising 10 said valve to open said outlet.

9. In a beverage dispensing device, a chamber having an inlet for beverage under gas pressure and having an outlet for gas, a valve normally closing said outlet, and an 15 expandible receptacle communicating with said chamber and engaging said valve and operable under expansion by pressure of gas to engage said container and effect raising of said valve to vent said outlet.

20 10. In a beverage dispensing device, a container having valve controlled inlet and outlet passages for the admission and discharge of beverage under gas pressure and having an outlet for gas, a valve controlling 25 said outlet, and gas receiving means operable under variations of pressure controlled by said first mentioned valve for actuating said outlet valve to regulate pressure of gas in said chamber.

30 11. In a beverage dispensing device, a chamber having a valve controlled inlet and outlet for beverage under gas pressure, and a resilient receptacle for receiving and storing gas from beverage admitted to said chamber upon opening said valve controlled inlet and for setting up pressure to discharge beverage from said chamber upon closing said inlet and opening said valve controlled outlet.

40 12. A beverage dispensing device comprising in combination, a beverage supply container having a valve controlled inlet and an outlet for beverage under gas pressure, a beverage chamber within said container communicating with said inlet and outlet for beverage and having an outlet for gas, a valve controlling said outlet for gas, and pressure actuated means controlled by said first named valve for actuating said 45 second named valve to regulate pressure of gas in said chamber.

50 13. A beverage dispensing device comprising in combination a beverage supply container, a beverage chamber within said

55 container having an inlet and an outlet for beverage, under gas pressure and having an outlet for gas, a valve exterior of said container controlling said inlet and outlet for beverage, a valve exterior of said beverage chamber controlling said outlet for gas, and a gas storage chamber controlling said last named valve and controlled by variations of pressure induced by actuation of said first named valve.

60 14. A beverage dispensing device comprising in combination, a container having inlet and outlet pipes for conducting beverage under gas pressure, a beverage chamber in communication with said inlet and outlet pipes within said container and having an 65 outlet for gas, a valve on said container controlling said inlet and outlet pipes, a valve on said beverage chamber controlling said outlet for gas, and a buoyant container for gas in communication with said beverage 70 chamber and controlling said last named valve under variations of pressure in said chamber induced by actuation of said first named valve.

75 15. In a beverage dispensing device, the combination with a container having valve controlled means for circulating and delivering beverage under gas pressure, of a beverage chamber extending vertically from within said container and having an inlet 80 and an outlet for beverage in communication with said circulating means and having an outlet for gas at the top of said chamber, means for discharging beverage within 85 the upper portion of said chamber to liberate the gas therein, and means controlling said outlet for gas and maintaining pressure in said chamber less than that under 90 which said beverage is admitted through 95 said valve controlled means.

100 16. In a liquid dispensing device, a chamber having an inlet and an outlet for liquid under gas pressure, and yieldable means associated with said chamber for receiving and storing gas evolved with the inlet of liquid thereto and for returning such gas to said chamber with the outlet of liquid therefrom.

In testimony whereof we sign this specification.

CHARLES M. EARL
BENJAMIN F. WHEELER.
